CHILD'S SLEEPING BAG

Ruth A. Peterson, Gary, Ind.

Application April 19, 1947, Serial No. 742,681

2 Claims. (Cl. 2—69.5)

1

My invention relates to improvements in sleeping bags for children and it more especially includes the features described in the following specification and pointed out in the annexed claims.

The purpose of my invention is to provide a self-contained sleeping bag unit; that is made in different sizes for different aged children; that is provided with an inner layer of cotton; that uses a virgin wool for the inner and outer layers which comprise a wool batten between the inside cotton blanket and the outside wool blanket; that is quilted throughout the layers to prevent lumping; that is washable throughout; that has the arms entirely closed except for older children; that has a drawstring under the arms; and an opening on the shoulder served by conventional snaps.

With these and other related ends in view I illustrate in the accompanying drawing such an instance of adaptation as will disclose the broad underlying features of the invention without limiting myself to the specific details shown thereon and described herein.

Fig. 1 is a front elevation of a completed unit.

Fig. 2 is a cross section on the line 2—2 of the different layers.

Fig. 3 is an enlarged section of a composite layer.

Fig. 4 is a detached section of a modified edge.

In practicing my invention I may modify the structure of the child's sleeping bag in whatever direction that the exigencies of varying conditions may demand without departing from the broad spirit of the invention.

The sleeping bag comprises a chest portion 1, a flared skirt portion 2, closed arm portions 3, a neck-line 4, and a snap fastener 5 on an opened shoulder 6. The inside layer 7 is a cotton blanket, the intermediate layer 8 is a 100% wool batten, and the outside 9 is a 100% wool blanket.

The three layers are quilted in any desired spacing and direction throughout as instanced at 10, and the entire garment is closed all around its perimeter by the seamed edges 11. The layers 7, 8, and 9 may have a separate cloth cover for each layer as shown in Figure 3 to form a modified completed garment.

A child's sleeping bag is especially desirable to ease the mother's work and free her from worries while the child is safely enclosed during the night or at any other time.

It is not unusual for a child, when covered with ordinary blankets, to squirm more or less

and leave its hands and feet uncovered and growing cold.

Whatever precautions are taken to wrap a child in a blanket and pin it securely all around like a papoose, they are not sufficient because very soon the hands will be out and the body can have very little movement while the child has to lie in one position all night, naturally producing fretfulness. The problem is to completely cover the child, of course, omitting the head, so that it will be kept covered through the night without exposure and be kept free from the risk of being smothered.

The entire garment is closely quilted throughout the different layers of which the inside is of cotton blanketing to satisfy children that are allergic to wool. The quilting prevents knotting and makes the garment serviceable after washing. The separate arm extensions prevent getting the arms into the bag. The drawstring at the waist brings the sides up as closely as desired and the snap fastening on the shoulder makes the interior immediately accessible.

If desired, there may be a snapped opening 5 on each shoulder. As shown in Fig. 2, the composite layers are in parallel relation with the inner layers 7, facing each other, and they are held all around the perimeter of the garment by stitching at 11. A binding 12 is sewn on all the edges to complete the garment.

As a modification of the method for securing the outer edges of the assembled composite layers, they may be sewn together at the edges as shown in Fig. 4, by first assembling the composite layers in reverse order with the final inner layers 7 on the outside; and then stitching them together at 11 (Fig. 4) similar to the stitching 11 on Fig. 2. Then, the garment is turned inside out to bring the inner layers 7, facing each other, as in Fig. 2; thus completing the garment without the use of binding 12 on the edges. The numbers 13 and 14 represent the two completed layers.

It is, of course, understood that the child's sleeping bag may be marketed in three or more different sizes, such as a light, medium, and a very heavy weight garment. It is further understood that I may change the sizes and weights to meet different demands as they arise without departing from the broad spirit of the invention.

What I claim is:

1. A child's sleeping bag which comprises a unitary enclosing garment for every portion of the child but its head, a plurality of layers of 55 different materials comprising an inner layer of

cotton, and encased intermediate wool batten, and a separately encased outer wool blanket, and a plurality of quilting seams passing through all the layers.

2. In a child's sleeping bag, alternate cotton and wool layers separately encased, an edge opening for the neck of the child, a snapped-shoulder opening, a waist drawstring, and two-directional quilting throughout the superimposed layers to make the garment washable without lumping the material in any of the layers.
